[57] CLAIM

The ornamental design for a portion of a crib, as shown and described.

DESCRIPTION

FIG. 1 is a front perspective view of a portion of a crib showing our new design;
FIG. 2 is an elevational view of a first side of the portion of a crib;
FIG. 3 is an elevational view of a second side of the portion of a crib opposite that shown in FIG. 2; and,
FIG. 4 is a bottom plan view of the portion of a crib. The broken line showing of the remainder of the crib is for illustrative purposes only and forms no part of the claimed design.
